UNITED STATES PATENT OFFICE.

PHILIPP SCHAUBLE AND LOUIS DOHM, OF ELIZABETHPORT, NEW JERSEY.

IMPROVEMENT IN CANDLESTICKS.

Specification forming part of Letters Patent No. 173,241, dated February 8, 1876; application filed January 7, 1876.

To all whom it may concern:

Be it known that we, PHILIPP SCHAUBLE and LOUIS DOHM, of Elizabethport, Union county, New Jersey, have invented a new and Improved Candlestick, of which the following is a specification:

Our invention consists of a coiled wire fixed upon a suitable base to serve for the tube of the ordinary candlestick, and having the upper end terminate in a hook for hanging it up readily, and also having a cup for the bottom of the candle, with a stem projecting out from it through the space between the coils, to raise and lower the cup by screwing it up and down, and to serve for a handle for carrying the candlestick about.

Figure 1 is a side elevation of our improved candlestick, and Fig. 2 is a top view.

Similar letters of reference indicate corresponding parts.

A is the coiled-wire candle-holder; B, a

metal plate for a base to hold it upright; C, the hook, in which the upper end of the wire terminates for hanging up the candlestick temporarily. D is the cup for the bottom of the candle, and E is the handle for the cup and for the candlestick.

Having thus described our invention, we claim as new and desire to secure by Letters Patent—

1. The coiled-wire candlestick A, having the upper end terminating in a hook, C, substantially as specified.

2. The combination of the cup D and a handle, E, with the coiled-wire candlestick A, substantially as specified.

PHILIPP SCHAUBLE.
LOUIS DOHM.
